UNITED STATES PATENT OFFICE.

CHARLES A. HONSINGER, OF DETROIT, MICHIGAN.

BANK FIXTURE.

Application filed April 24, 1925. Serial No. 25,568.

To all whom it may concern:

- Be it known that I, CHARLES A. HONSINGER, a citizen of the United States, residing at Detroit, in the county of Wayne and 5 State of Michigan, have invented certain new and useful Improvements in Bank Fixtures, of which the following is a specification, reference being had therein to the accompanying drawings.
- 10 This invention relates to a bank fixture adapted to be placed in bullet proof partitions to permit of communication being established from one side of the partition to the other and a fire arm manipulated in the 15 fixture.
- My invention aims to protect the lives of bank officials and clerks by providing bullet proof transparent partitions and in order that a bank customer and bank clerk may 20 carry on a conversation through such partitions a speaking tube device is mounted in the partition, said device including baffle members which will prevent the passage of bullets or other projectiles through the 25 speaking tube. Adjacent the speaking tube is a one-way trap door adapted to be actuated by a fire arm in the hands of a bank clerk and the trap door is inoperative by a bandit or other person outside of the 30 partition, but permits of a bank clerk aiming a fire arm in different directions with a view of injuring the bandit or preventing his escape.
- The construction of my device will be 35 hereinafter specifically described and then claimed, and reference will now be had to the drawings, wherein—
- Figure 1 is a front elevation of the device;
- 40 Fig. 2 is a vertical sectional view of the same mounted in a partition or bank fixture;
- Fig. 3 is a rear elevation of the device;
- Fig. 4 is a rear elevation of a portion of 45 the device showing the trap door;
- Fig. 5 is a vertical sectional view of the same showing a fire arm holding the trap door in an open position;
- Fig. 6 is a horizontal sectional view of a 50 portion of the trap door illustrating the manner in which a fire arm has a wide range of action, and
- Fig. 7 is an elevation of a modified form of trap door.
- 55 In the drawing, the reference numeral 1 denotes a partition, wall or other bank fixture which may be made of thick transparent bullet proof glass. The partition is provided with an oblong opening 2 and it is in this opening that I mount my device for 60 establishing communication between both sides of the partition.
- The device comprises a front plate 3 having a trap door opening 4 adjacent its upper end and an inwardly projecting 65 speaking tube 5, adjacent its lower end. This front plate fits against the outer side of the partition 1 and may be provided with an escutcheon plate 6 lending a degree of ornamentation to the device. Attached to 70 the inner face of the front plate 3, by spot welding or any suitable means is a connecting plate 7 and attached to the connecting plate 7, by screws or other fastening means 8 is a rear plate 9 which fits against the 75 inner face of the partition 1 about the opening 2 thereof and cooperates with the plates 3 and 7 in holding the device firmly in the partition opening 2.
- The connecting plate 7 is arranged about 80 the trap door opening 4 and pivotally mounted in the trap door opening 4, is an outwardly swinging trap door 10 having pintles or other pivotal means 11 supporting the lower edge of the door in the 85 lower edges of the opening 4 so that said trap door may be swung bodily outwardly. The connecting plate 7 has a transverse spring support 12 for the coiled portions 13 of a spring 14, said spring having a portion thereof attached to the connecting plate 7 by a screw 15 or other fastening means and the ends 16 of said spring extend under a cleat 17 attached to the inner face of the trap door 10. The tension of the spring is 90 adapted to hold the trap door normally closed against opening walls 18 of the connecting plate, so that the outer face of the trap door will be flush with the outer face of the front plate 3. With the trap door neatly fitting in the opening 4 it will be impossible for an outsider to open the door 10 and the connecting plate 7 prevents the trap door from being forced inwardly. This arrangement, however, does not prevent a 105 bank clerk or person at the inner side of the partition 1 from forcing the door 10 outwardly and open and this may be accomplished by the barrel 19 of a fire arm. It is only necessary to forcibly place the muzzle 110 of the barrel 19 against the upper portion of the trap door 10 and as the door is forced

open the barrel 9 will ride on to the upper edge of the open trap door, as shown in Fig. 5, and may be swung in various directions, as indicated in Fig. 6, thus permitting of a wide range of action for the fire arm.

To facilitate quickly opening the trap door 10 by the barrel 19 the rear plate 9 is formed with somewhat of a funnel shaped guide 20 extending in proximity to the inner face of the trap door 10.

The rear plate 9 has an opening 21 communicating with the speaking tube 5 and disposed parallel to the rear plate are apertured baffle members 22 and 23 spaced apart by sleeves 24 and connected to lugs 25 of the rear plate 9 by screws 26 or other fastening means. The apertures of the baffle member 22 are staggered with relation to the apertures of the baffle plate 23 so that an outsider cannot successfully manipulate a fire arm in the speaking tube. The baffle members do not interfere with the voice passing either way through the speaking tube, and lend a degree of protection to any bank clerk adjacent the device.

Instead of pivotally mounting the trap door 10, a sliding door 27 may be employed and guided by screws 28 with springs 29 attached to the screws for supporting the slide trap door in a raised or closed position relative to an opening 30. The upper edge of the slide trap door may be provided with a latch or actuating member 31 that may be struck by the barrel 19 of the fire arm to open the trap door and permit of the barrel being projected through the opening 30. I have thought of other ways of arranging the trap door to be operable from the inner side of the bank partition or fixture and non-operative by bandits or persons outside of the partition. It is believed, however, that a pivoted trap door affords a quick action on the part of a bank clerk as the fire arm barrel may be brought to an aiming position and projected against the trap door to be immediately discharged on opening the door. The transparent partition contributes to a successful manipulation and discharge of the fire arm through the device which affords a gun port that may permit of a bandit being killed by a bank clerk or detained until captured.

Bank fixtures now installed have the device arranged at windows where bank customers are served, the device being placed at a convenient distance above the counter and used in connection with my deal plate

or bank safety device, disclosed in Patent No. 1,460,584, dated July 3, 1923. It is also used at other places throughout the bank fixtures where communication is to be established from one side of the fixture to the other side, and while in the drawing there is illustrated the preferred embodiment of my invention, it is to be understood that the structural elements are susceptible to such variations and modifications as fall within the scope of the appended claims.

What I claim is:—

1. The combination with a partition having an opening, of plates clamped against said partition at the opening thereof, a speaking tube carried by one of said plates and extending into the partition opening, an outwardly opening trap door supported by the same plate, and baffle members carried by the other of said plates at said speaking tube.

2. The combination called for in claim 1, and means between said plates adapted to hold said trap door normally closed.

3. The combination called for in claim 1, and a guide carried by the last mentioned plate and extending in proximity to the inner side of said trap door.

4. The combination with a partition having an opening, a front plate, a rear plate, and a connecting plate in the partition opening connecting said front and rear plates, a speaking tube carried by the front plate, and baffle members carried by the rear plate at the inner end of said speaking tube.

5. The combination called for in claim 4, and a normally closed outwardly opening trap door carried by said front plate.

6. The combination called for in claim 4, and a normally closed outwardly opening trap door carried by said front plate and a gun barrel guide carried by the rear plate and extending in proximity to said trap door.

7. The combination with a partition having an opening, of plates carried by said partition at the opening thereof, a speaking tube carried by one of said plates and extending into the partition opening, an outwardly opening trap door supported by the same plate, and baffle members carried by the other of said plates at said speaking tube.

In testimony whereof I affix my signature.

CHARLES A. HONSINGER.
